UNITED STATES PATENT OFFICE.

COON A. DEAS, OF ROCK HILL, SOUTH CAROLINA, ASSIGNEE TO ANDERSON MOTOR COMPANY, OF ROCK HILL, SOUTH CAROLINA, A CORPORATION OF SOUTH CAROLINA.

ELECTRICAL SWITCH.

Application filed August 16, 1922. Serial No. 532,201.

To all whom it may concern:

Be it known that I, COON A. DEAS, a citizen of the United States, residing at Rock Hill, in the county of York and State of South Carolina, have invented certain new and useful Improvements in Electrical Switches; and I do hereby declare the following to be a full, clear, and exact description of the invention, such as will enable others skilled 10 in the art to which it appertains to make and use the same.

This invention relates to new and useful improvements in electrical switches and more particularly to a switch adapted to be 15 connected with the headlights of a motor vehicle for dimming or reducing the headlights when passing another vehicle, the main object of the present invention being the provision of a switch of this character 20 adapted to be located in close proximity to the clutch pedal and to be engaged by the foot of the operator when about to pass another vehicle so as to dim or reduce the glare of the headlights to avoid accidents 25 caused by the constant glare of the headlight in the approaching party's eyes.

A further object of this invention is the provision of a foot operated switch located in a convenient position for engagement 30 with the operator's foot and used in connection with the ordinary switch controlling the headlights of a motor vehicle so that the lights may be dimmed or reduced by the foot, or if necessary, to retain them in a reduced 35 state, the hand operated switch may be utilized until it is desired to return the lights to their full strength.

With the above and other objects in view, the invention consists in the novel features 40 of construction, combination and arrangement of parts hereinafter more fully set forth, pointed out in the claims and shown in the accompanying drawings, in which:

Figure 1 is a diagrammatic view showing 45 my improved switch used with connections for single bulb headlights;

Fig. 2 is a similar view showing the same used with connections for double bulb headlights;

Fig. 3 is a side elevation of my improved 50 switch, and

Fig. 4 is a vertical sectional view.

In carrying out my invention, the improved foot dimming switch is preferably 55 located between the hand switch indicated at

1 and the headlights 2, whereby pressure exerted upon the foot switch will readily dim the lights and if it is found necessary to continue the dimming of the lights for a considerable length of time and also permit the operator to have the use of his foot for operating the clutch pedals, the hand switch 1 may be thrown to the proper position until it is again desired to use the full strength of the lights.

It is proposed to have my improved foot switch in close proximity to the clutch pedals so that it is will be readily accessible to the foot of the operator for dimming the lights when desired without the necessity of the operator having to use his hands and includes in its construction, a base plate 3 provided with binding posts 4, to which the connecting wires 5 are attached, said wires having suitable connection with the hand switch 1 and the battery 6. This base member 3 is preferably formed of composition material which is non-conductive and provided with an opening having arranged therein a cylindrical casing 7 provided with perforated flanges 8 at its upper end whereby suitable fastening means may be inserted through said flanges for attaching the switch in position upon the foot board of the vehicle. Extending upwardly from the flanged portion 8 is a sleeve 9 having a central bore communicating with an opening in the flanged portion 8 communicating with the casing 7. Movable within this bore and extending into the casing 7 is a pin 10, the outer end of which is connected to the outer end of the movable cap member 11, the inner end of said cap member fitting over the sleeve 9 and movable thereon.

Mounted upon the inner end of the pin 10 or the end which projects into the casing 7, is a collar 12 held in position by means of a washer 13 which is fitted on the inner end of the pin 10. This collar 12 is preferably formed of any suitable non-conductive material and embedded within portions of this collar 12 at its inner end is a metallic ring 14 adapted to normally engage the arcuate contact points 15 of the arms 16. These arms 16 are provided with angular portions 17 adapted to be mounted upon the binding posts 4 as clearly disclosed in Fig. 4, so that when the pin 10 is in its normal position, as illustrated in Fig. 4, a continuous current will be supplied to the headlights 2 to pro-

vide for the proper strength of the rays of light. It will be apparent that when downward pressure is exerted upon the outer end of the cap member 11, the pin 10 will be moved inwardly to disengage the ring 14 from the contact points 15, thus cutting off the direct supply of current to the headlights and in order to provide for a continuation of the current to the headlights at a reduced strength, a resistance coil 18 is embedded within an outer casing 19. This outer casing is formed of any suitable fibrous material and as the resistance coil is connected to the binding posts 4, providing a continuation of the electrical supply to the headlights. The resistance offered however, by the wire 18, is such that when the current is forced to pass through it, the lights will burn dimly.

Arranged within the cap member 11 and surrounding the pin 10 is a coil spring 20, one end of which bears against the outer end of the sleeve 9, while the other end bears against the outer end of the cap member 11, the tension of this spring normally retaining the ring 14 and the contact points 15 into engagement so as to provide the proper amount of current to the headlights, but when it is desired to dim the lights, and send the current through the resistance coil 18, the operator presses his foot upon the outer end of the cap member 11, forcing the same downwardly toward the flanged portion 6, at the same time pushing the rod 10 inwardly to disconnect the contact points 14 and 15. As soon as the operator's foot is released from the outer end of the cap member 11, the tension of the spring 20 will return the cap member and the pin 10 to their normal positions, bringing the ring 14 again into engagement with the contact points 15.

In using my improved foot switch, the lighting switch with the regular dimming resistance is mounted upon the instrument board and connected up in the usual way for dimming lights with the hand switch, then the headlight wire is extended through the foot dimming switch in which the conductor is of sufficient size to offer practically no resistance while contact is made, but when the contact is broken the current is shunted across the switch through the resistance coil 18 with equal resistance to that in the hand dimming switch, thus dimming the lights the same amount as with the hand dimming arrangement.

In case double bulb headlights are used, the dim side of the hand switch is connected directly to the small bulbs and the bright side is connected to the large bulbs with the

foot switch placed in the line in the same manner as with the single bulb arrangement. From this it will be apparent that by actuating the foot switch, the lights may be readily dimmed, but should it be desired to retain the lights in a dim state for any length of time, and in order to give the operator free use of his feet, the hand switch may be thrown to the dimmed position and retained there until it is desired to use the full strength of the lights again.

From the above description taken in connection with the accompanying drawings, it will be readily apparent that I have provided a simple, inexpensive and effectively operative device which can be quickly and readily attached to motor vehicles and arranged between the hand switch and the headlights for dimming the lights by the use of the foot without the necessity of removing the hands from the steering wheel while passing another vehicle.

I claim:

1. A switch of the class described comprising a base member, binding posts carried by said base member, a casing extending upwardly from the base, a movable cap member slidably mounted on the casing, a reciprocating plunger carried by the cap member and having one end projecting within the casing, a ring carried by the inner end of the plunger, contact members connected with the binding posts and normally engaging said ring whereby downward movement of the cap member will disengage the contacts from the ring and a resistance coil supported around the casing and embedded within an outer casing and having connection with the binding posts, as and for the purpose set forth.

2. A device of the class described including a base member, binding posts carried thereby, a casing extending upwardly above the base, a spring actuated cap member slidably supported by the casing, a plunger connected with the cap member and extending into the casing, an insulating sleeve upon the inner end of the plunger, a ring surrounding one end of the insulated sleeve, contact members carried by the binding posts and normally engaging said ring to complete a circuit between said posts, said cap member being manually operated to reciprocate the plunger and move the contacts from the ring onto the insulated sleeve and a resistance coil mounted upon said casing and embedded within an outer casing and connecting the binding posts.

In testimony whereof I affix my signature.

COON A. DEAS.
